UNITED STATES PATENT OFFICE.

ALEXANDER BRZOSTOWSKI, OF MOUNT CARMEL, PENNSYLVANIA.

TRACK-RAIL FASTENER.

Application filed April 27, 1922. Serial No. 557,026.

To all whom it may concern:

Be it known that I, ALEXANDER BRZOSTOWSKI, a citizen of Poland, residing at Mount Carmel, in the county of Northumberland and State of Pennsylvania, have invented certain new and useful Improvements in Track-Rail Fasteners, of which the following is a specification.

This invention relates to track rail fastening means, and it has for an object to provide a novel and efficient type of rail fastening means designed to ensure against lateral movement or vibration of the rail.

For further comprehension of the invention, and of the objects and advantages thereof, reference will be had to the following description and accompanying drawings, and to the appended claims in which the various novel features of the invention are more particularly set forth.

Fig. 1 is an enlarged vertical section, transversely of the rail, this view being taken on the line 1—1 of Fig. 2.

Fig. 2 is a plan view of the device as illustrated in Fig. 1.

Referring now to the drawings, the reference numeral 10 indicates a track rail.

I provide a tie-plate 11' having integral rail-engaging blocks such as 12' at opposite ends, and which rests on a wooden tie or sleeper 20. Engaged with the inner side of each rail is a block 21 seating on the tie-plate 11', the latter having an abutment lug 22 projecting upwardly at the side of the block 21 removed from the rail 10, and beyond the flat bottom wall of the block, the latter as here shown presenting a flat bottom wall at one side of which is a vertical wall engaging the rail, angular stiffening ribs 21' being provided.

To secure the block 21 in place I provide a pair of abutment links 23 and 24 respectively which extend toward one another and have their opposed ends resting on the bottom wall of the block and engaging the abutment lug 22 and the vertical inner wall of the block 21, respectively. These links have forked meeting extremities 23' and 24' which abut against one another, holding the links in the inclined position shown. A T-headed spike 25 is driven into the sleeper, passing downward through the crotch of the extremity 23' and through a suitable slot 26 in the block 21 and tie-plate. As will be apparent, when the head 25' of spike 25 engages the overlapped ends of the two

links 23 and 24 it tends to straighten the same out, and in consequence forces the block 21 against the rail 10, holding the latter securely against any transverse vibration or motion. As here shown, the link 24 is considerably shorter than the link 23 so as to exert a downward force on the block 21 as well as a lateral force.

Having thus described my invention what I claim as new and desire to protect by Letters Patent of the United States is as follows:

1. In combination with a track rail, a tie-plate having a block-like projection engaging the outer side of said rail and an abutment lug spaced at a distance from the inner side of said rail, a block positioned on said tie-plate between said abutment lug and the rail, and means bearing on said block and abutment lug to force the block against the rail, and including a pair of abutting links of relatively different lengths adapted to have a toggle action on said block.

2. In combination with a track rail, a tie-plate having a block-like projection engaging the outer side of said rail and an abutment lug spaced at a distance from the inner side of said rail, a block positioned on said tie-plate between said abutment lug and the rail, and means bearing on said block and abutment lug to force the block against the rail, said means including a pair of inclined links having engaging abutting ends, and being adapted to have a toggle action on said block.

3. In combination with a track rail, a tie-plate having a block-like projection engaging the outer side of said rail and an abutment lug spaced at a distance from the inner side of said rail, a block positioned on said tie-plate between said abutment lug and the rail, and means bearing on said block and abutment lug to force the block against the rail, said means including a pair of inclined links having engaging abutting ends, and means pressing said ends downward.

4. In combination with a track rail, a tie-plate having a block-like projection engaging the outer side of said rail and an abutment lug spaced at a distance from the inner side of said rail, a sleeper on which said tie-plate rests, a block positioned on said tie-plate between said abutment lug and the rail and presenting a bottom wall resting

on said tie-plate and a vertical wall engaging the rail, a pair of inclined abutment links positioned on said bottom wall and having opposed ends bearing respectively 5 on said vertical wall and abutment lug, and having forked overlapping and abutting meeting ends, and a fastening element pressing downward on the said meeting ends.

- 10 5. In combination with a track rail, a tie-plate having a block-like projection engaging the outer side of said rail and an abutment lug spaced at a distance from the inner side of said rail, a sleeper on which said 15 tie-plate rests, a block positioned on said tie-plate between said abutment lug and the rail and presenting a bottom wall resting on said tie-plate and a vertical wall engaging the rail, a pair of inclined abutment

links positioned on said bottom wall and 20 having opposed ends bearing respectively on said vertical wall and abutment lug, and having forked overlapping and abutting meeting ends, and a fastening element pressing downward on the said meeting 25 ends, said fastening element comprising a T-headed spike having its shank inserted between the forks of said ends and engaging in the said sleeper.

In testimony whereof I have affixed my 30 signature.

ALEXANDER ^{his} X BRZOSTOWSKI.
mark.

Witnesses to his mark—

V. CSAMERDA,
J. G. FALEUB.
